Attorney

UNITED STATES PATENT OFFICE.

ALLEN S. MILLER, OF BALTIMORE, MARYLAND.

TIME FUSE.

Application filed June 25, 1924. Serial No. 722,369.

To all whom it may concern:

Be it known that I, ALLEN S. MILLER, a citizen of the United States, residing at Baltimore, in the State of Maryland, have invented certain new and useful Improvements in Time Fuses, of which the following is a specification.

This invention relates to time fuses for explosive shells, and particularly to the construction of the timing rings therefor.

In my allowed application, Serial No. 685,229, filed January 9, 1924, I describe and claim a method of and apparatus for controlling the rate of burning of time powder trains. This method involves the maintenance of a constant absolute pressure on the burning train by the use of a constant vent orifice for the gases evolved in burning, and the success of the method is dependent on the evolution of the gases at a constant rate. This is easily accomplished with the single time ring shown in that application, but cannot be readily accomplished with the conventional type of double time ring, for the reason that in certain adjustments of the rings the train in the first ring will continue to burn after the train in the second ring has commenced to burn, with a consequent increase of the rate of evolution of gases. This arises from the fact that the flash hole from the concussion primer to the first ring and the flash hole from the second ring to the charge are in a fixed angular relation to each other.

The present invention relates to a construction of the rings such that each ring will transfer the flame to the next just as it burns out, and not before. This permits the use of a multiple ring construction in which the rate of burning can be successfully controlled by a fixed orifice in the manner characteristic of said prior application. The invention thus increases the utility of my prior invention, particularly in its application to long range shells, and is also of general utility in any case where the evolution of gases at a constant rate is necessary or desirable.

Generally stated, the invention involves the construction of the fuse so that the front portion of the body of the fuse, which carries the concussion primer, is swiveled and may be rotated relatively to the shell, and so that the first ring turns with such forward portion of the body. Thus the flash

from the concussion primer is transmitted to the beginning of the train in the first ring in all adjustments. For all timing within the full time range offered by the first ring the flame is transmitted to the charge in the shell from the first ring through the pellet at the beginning of the second ring. For all timings within the added range offered by the second ring the two rings are adjusted relatively to each other so that the flame is transmitted from the end of the first ring to the pellet at the beginning of the second, and the two rings are so adjusted relatively to the shell that the flame is transmitted to the charge after the train in the second ring has burned the desired distance.

This inventive concept may obviously be embodied in fuses having more than two rings, but as two show the principle and ordinarily are sufficient I have chosen this embodiment for illustration.

The accompanying drawing shows the improved fuse in longitudinal axial section, as it appears when mounted on the nose of a shrapnel shell.

A part of the casing of the shell appears at 5 and is closed at its forward end by a plug 6 threaded therein. The body of the fuse consists of two portions 7 and 8. The rear portion 7 is threaded into the plug 6. The front portion 8 of the body is swiveled on the rear portion 7 and is retained in place by means of a bolt or rivet 9. The usual chamber for the magazine charge 10 is formed in the rear section 7 of the body and to this leads the usual passage 11 containing an ignition pellet 12.

Two time rings 13 and 14 are provided. The rear ring 13 is swiveled on the rear portion 7 of the fuse body and is provided with a powder train 15 and with an ignition pellet 16 at the beginning of that train.

In one adjustment of the ring 13 relatively to the rear portion 7 of the body, the flash may be transmitted from the pellet 16 to the pellet 12. In other adjustments the flame must follow the train 15 from the pellet 16 to the pellet 12.

The forward timing ring 14 is mounted on the forward portion 8 of the fuse body and is keyed or splined thereto by means of a key or feather 17 so as to turn therewith.

The ring 14 is provided with a powder train 18 so arranged that the angular adjustment of the ring 14 relatively to the

ring 13 permits the flame to be transmitted to the pellet 16 from any desired point in the length of the train 18.

Mounted in the forward end of the portion 8 of the body is the concussion plunger 19, which is retained by the usual resistance ring 20 and which carries the usual concussion primer 21. The firing pin for the concussion primer is shown at 22 and 10 may conveniently be formed on the head of the bolt or rivet 9.

A flash hole 23 transmits the flash from the concussion primer 21 directly to the beginning of the train 18 in the ring 14. The 15 flash hole 23 is formed partly in the ring 14 and partly in the portion 8 of the body, but since these two parts turn together a constant registry is had. In effect, the ring 14 and the portion 8 of the body are one 20 piece but it is more convenient to manufacture them as two separate pieces connected together.

The concussion primer structure is housed by the cap 24 and this cap is provided with 25 vent ports 25 for the powder gases evolved by the burning trains. The ports 25 lead to an orifice 26 whose size is determined by considerations hereinafter outlined, and this orifice serves to maintain a constant pressure on the burning powder trains so long as 30 the powder gases are evolved at a substantially constant rate.

For convenience in manufacture, the orifice 26 is formed in a plug 27 which is 35 threaded into the forward end of the cap 24. A false cap 28 having relatively large vent ports 29 is also threaded onto the forward end of the cap 24.

The size of the orifice 26 is determined by 40 the following considerations:

If a gas or a mixture of gases is discharged under a constant head pressure through a fixed orifice, the rate of flow will vary as an inverse function of the pressure 45 on the discharge side of the orifice, provided this pressure be above a definite critical value, which, expressed as a function of the head pressure, is a constant for the particular gas. Below such critical value changes 50 of pressure on the discharge side do not affect the rate of flow.

To take advantage of this phenomenon, I so coordinate the train and the size of the orifice 26 that the train burns under a constant absolute pressure, which is so related 55 to the maximum atmospheric pressure that all variations in atmospheric pressure occur below such critical value and hence have no effect upon the rate of flow through the orifice 26. This characteristic action of the 60 vent 26 is claimed in my prior application above identified and hence is not broadly claimed herein.

Obviously, it is essential that the powder 65 trains evolve gases at a definite quantity

rate, and this is made possible by the construction of the fuse above described. With the rear ring 13 adjusted so that the flash from the pellet 16 is transmitted directly across the ring to the pellet 12, the train 15 in the rear ring 13 is functionless for it can be ignited and burned only after or simultaneously with the ignition of the magazine charge 10. With the ring 13 in this position the ring 14 may be adjusted relatively 70 thereto so that any desired portion of the train 18 may be burned before the pellet 16 is ignited.

For longer ranges, the rings 13 and 14 are adjusted relatively to each other so that 80 the pellet 16 registers with the end of the train 18 and hence is ignited just as this train burns out. With the rings 13 and 14 so relatively adjusted, it is possible to adjust both rings relatively to the body portion 7, so that the pellet 12 is ignited after any desired portion of the train 15 has burned. In this way, it is possible to get any time adjustment up to that afforded by the successive burning of the two trains and yet 85 at no time are portions of two trains burning simultaneously.

Simultaneous burning of portions of two trains is characteristic of many adjustments of conventional time fuses and is the reason 90 why such time fuses cannot be satisfactorily controlled, as to the pressure under which they burn, by means of a constant vent orifice.

The manipulation in setting the time 100 rings is familiar to those skilled in the art, with the exception of the details already pointed out, and hence need not be further described.

What is claimed is:

1. The combination of a multiple time ring fuse constructed and arranged to evolve powder gases at a constant time rate in all timing adjustments thereof; and a constant area throttling orifice controlling 110 the discharge of powder gases evolved by said fuse and so dimensioned as to exert a constant back pressure thereon.

2. The combination of a fuse including a plurality of uniform time powder trains arranged to burn successively and adjustable to transmit the flame to the charge to be ignited at any point in the aggregate length of the trains; and a constant area throttling orifice controlling the discharge of 115 powder gases evolved by said trains and so dimensioned as to exert a constant back pressure thereon.

3. The combination of a shell having an explosive charge; a combined body and timing ring member swiveled on said shell; a concussion primer and a time train, arranged to be ignited thereby, both mounted in said combined member; a second timing ring swiveled on said 120

shell and adjustable relatively to said shell and to said combined member; and a time train in said second timing member adapted to be ignited by said first train and 5 to transmit the flame to said charge.

4. The combination of a shell having an explosive charge; a body member swiveled on said shell; a time powder train mounted to turn with said body member; a concussion primer mounted in said body member and arranged to ignite the powder at the beginning of said train; and a second timing member including a second time powder train adjustable relatively to said shell and 10 to said body member, and serving in a given adjustment relatively to the shell to transmit flame to said charge directly from chosen points in the length of the first train according to the concurrent relative ad- 15 justment of the body member thereto, and serving in a given adjustment relatively to said body member to transmit flame to said charge from the end of said first train through chosen lengths of the second train 20 according to the concurrent adjustment of the second timing member relatively to the shell. 25

5. The combination of a shell having an explosive charge; a body member swiveled 30 on said shell; a time powder train mounted to turn with said body member; a concussion primer mounted in said body member and arranged to ignite the powder at the beginning of said train; and a second timing member including a second time powder train adjustable relatively to said shell and 35 to said body member, and serving in a given adjustment relatively to the shell to transmit flame to said charge directly from chosen points in the length of the first train 40 according to the concurrent relative adjust-

ment of the body member thereto, and serving in a given adjustment relatively to said body member to transmit flame to said charge from the end of said first train 45 through chosen lengths of the second train according to the concurrent adjustment of the second timing member relatively to the shell; and pressure regulating means controlling the discharge of the gases evolved 50 by the trains when burning.

6. The combination of a shell having an explosive charge; a body member swiveled on said shell; a time powder train mounted to turn with said body member; a concussion primer mounted in said body member and arranged to ignite the powder at the beginning of said train; and a second timing member including a second time powder train adjustable relatively to said shell and 55 to said body member, and serving in a given adjustment relatively to the shell to transmit flame to said charge directly from chosen points in the length of the first train according to the concurrent relative adjust- 60 ment of the body member thereto, and serving in a given adjustment relatively to said body member to transmit flame to said charge from the end of said first train through chosen lengths of the second train 65 according to the concurrent adjustment of the second timing member relatively to the shell; and a constant area throttling vent, so proportioned relatively to the nature of the gases evolved by the trains when burn- 70 ing, and relatively to the maximum atmospheric pressure, as to maintain a constant gas pressure on said trains. 75

In testimony whereof I have signed my name to this specification.

ALTEN S. MILLER.
